UNITED STATES PATENT OFFICE.

H. C. HUNT, OF AMBOY, ILLINOIS.

IMPROVEMENT IN WEATHER-STRIPS FOR DOORS.

Specification forming part of Letters Patent No. 44,428, dated September 27, 1864.

To all whom it may concern:

Be it known that I, H. C. HUNT, of Amboy, in the county of Lee and State of Illinois, have invented a new and Improved Weather-Strip for Doors; and I do hereby declare that the following is a full, clear, and exact description thereof, which will enable others skilled in the art to make and use the same, reference being had to the accompanying drawings, forming part of this specification, in which—

Figure 1 is an outside view of a door partially open and having my invention applied to it; Fig. 2, a transverse section of the same, taken in the line *xx*, Fig. 1; Fig. 3, an outside view of the lower portion of a door with my improvement applied to it, the latter being partially in section or broken away.

Similar letters of reference indicate like parts.

This invention relates to a new and improved weather strip for doors, designed to prevent rain being driven by the wind underneath the door, and also to prevent the wind itself from passing underneath the door.

The invention consists in attaching a plate by means of joints to the lower part of a door and having a spring applied to the door behind the plate, all being so arranged that when the door is closed the plate will be in a vertical position in front of the door-sill and effectually prevent wind or rain from passing underneath it, while the plate will, as the door is opened, be raised under the action of the spring so as to be above the sill and not come in contact with it.

A represents a door-frame, and B a door hung to the frame A by hinges C in the usual way. D is the door-sill, constructed and applied in the ordinary way.

To the lower part of the door B at its outer

side there is suspended by joints *a a* a metal plate, E, the latter being allowed to swing freely and extending down a trifle below the bottom of the door, the plate fitting in a rabbit in the door. To the door B, directly behind the plate E, there is attached a spring, F, which may be constructed in any proper manner.

A flat spring is represented in Figs. 2 and 3.

When the door is closed, the ends of the plate E come in contact with the cleat or shoulder *b* at the side of the jam *c* of the door-frame, to which the nosing of the lock is attached, and said cleat presses down the plate E to a vertical position directly over the front of the sill D, as shown in Fig. 2, and said plate effectually prevents rain or wind from passing underneath the door between it and the sill. On opening the door the spring F turns up the plate E, so that the latter may pass back over the sill D and its lower edge be retained above the sill until the door reaches a closed state, or until the end of plate E comes in contact with cleat *b*.

The arrangement is extremely simple and the device may be applied at a small cost. The top of the sill D is covered by a metal plate, *c'*, between which and the door-sill there is a strip of listing, felt, or gum, *g*, which extends beyond the edge of the iron plate and forms a packing against which the strip rests when closed, rendering the joint impervious to wind and water.

I claim as new and desire to secure by Letters Patent—

The plate *c'*, when used in connection with the packing *g*, for the purpose specified.

H. C. HUNT.
